(57) **CLAIM**

The vehicle navigation unit with video disc player, as shown and described.

DESCRIPTION

FIG. 1 is a perspective view of a vehicle navigation unit with video disc player showing the new design;

FIG. 2 is a top view thereof;

FIG. 3 is a front view thereof;

FIG. 4 is a right-side view thereof;

FIG. 5 is a left-side view thereof;

FIG. 6 is a rear view thereof;

FIG. 7 is a bottom view thereof; and,

FIG. 8 is a front view thereof, shown with the power on for reference purposes only. The images on the screen of the vehicle navigation unit with video disc player with the power on do not form any part of the claimed design.

The broken lines are for environmental purposes only and do not form any part of the claimed design.
